CLAIM

The ornamental design for a pet friendly door guard, as shown and described.

DESCRIPTION

FIG. 1 is a perspective view showing the pet friendly door guard embodying the new design;

FIG. 2 is a rear elevation view thereof;

FIG. 3 is a front elevation view thereof;

FIG. 4 is a left side view thereof;

FIG. 5 is a top plan view thereof; and,

FIG. 6 is a bottom plan view thereof.

The right side view of the design is a mirror image of the left side view shown in FIG. 4.

(Continued)

The broken line showing of a vehicle in FIG. 1 depicts exemplary environment for purposes of illustration and does not form part of the claimed design.

1 Claim, 3 Drawing Sheets
